United States Patent Office.

JOHN S. DAVISON AND NICHOLAS LORTON, OF CRANBERRY, NEW JERSEY.

Letters Patent No. 81,261, dated August 18, 1868.

IMPROVED COVER FOR CHAMBERS AND OTHER VESSELS.

The Schedule referred to in these Letters Patent and making part of the same.

TO ALL TO WHOM IT MAY CONCERN:

Be it known that we, JOHN S. DAVISON and NICHOLAS LORTON, of Cranberry, in the county of Middlesex, in the State of New Jersey, have invented a new and improved Air-Tight Cover for Chambers and other Vessels; and we do hereby declare that the following is a full and exact description thereof, reference being had to the accompanying drawings, and to the letters of reference marked thereon, making a part of this specification, in which—

Figure 1 is a perspective view of our cover or lid.

Figure 2 is a perspective view of a wire hoop, which may form part of our cover.

Figure 3 is a representation of circular piece of India rubber, with the rim turned up, so that it can be stretched over the hoop.

Figure 4 is a view of our cover applied to a chamber.

Figure 5 is a view of a stone-ware pot, with our cover placed on it.

Similar letters of reference indicate corresponding parts in the several figures.

This invention relates to an improvement in covers or lids for chambers, crocks, and other vessels.

The object of the invention is to form an air-tight cover which may be readily and easily used. This object is attained by simply forming a wire ring, and stretching a piece or sheet of India rubber over it, thus forming the desired cover.

To enable those skilled in the art to fully understand and construct our invention, we will proceed to describe it.

A represents a circular sheet of caoutchouc or India rubber, either of a light or dark color, and one-sixteenth or one-thirty-second of an inch in thickness. An edge is formed with it, and turned up all around, as shown at b in fig. 4. This sheet of rubber forms the principal part of our invention, and is stretched over a wire ring or hoop, as shown in fig. 3.

When the wire is used in the construction of the cover, the upturned edge of the India rubber is turned down over the wire hoop and cemented fast, as shown in fig. 1, with a circular piece of rubber cloth cemented in the centre, for the purpose of strengthening the cover in connection with a knob, which knob is secured to the centre of the cover by an extra thickness of rubber or wood on the under side, thus making a good and durable cover.

When this cover is applied to a chamber or other vessel, its elasticity brings it into so close contact with the entire surface or top of the vessel or chamber that all air or offensive odor is effectually prevented from passing in or out of the chamber or vessel.

This lid or cover will be useful in hospitals or the sick-room at home, as it confines any offensive odor within the chamber. Nor is this the sole purpose for which it can be used, for it can be applied to any vessel needing an air-tight cover. It will be found valuable for preserving butter or lard, or any volatile substance requiring to be kept from the air.

Having thus described our cover and its various uses—

What we claim as our invention, and desire to secure by Letters Patent, is—

The formation of an air-tight cover, by means of caoutchouc or India rubber, when stretched over a hoop as herein described, the whole being arranged as and for the purpose above set forth.

JOHN S. DAVISON,
NICHOLAS LORTON.
